Primary Examiner — Michael A. Pratt(57) **CLAIM**

The ornamental design for a 3D fold target, as shown and described.

DESCRIPTION

FIG. 1 is a front perspective view of a 3D fold target, showing my new design;

FIG. 2 is a front elevation view thereof;

FIG. 3 is a right-side elevation view being a mirror image thereof;

FIG. 4 is a rear elevation view thereof;

FIG. 5 is a left side elevation view thereof;

FIG. 6 is a top plan view thereof;

FIG. 7 is a bottom view thereof;

FIG. 8 is left side cross-sectional view taken from 8-8 in FIG. 4; and,

FIG. 9 is a perspective view of the 3D fold target shown in an environment of use.

The broken lines in FIG. 1, FIG. 2 and FIG. 9 depict environmental subject matter and form no part of the claimed design.
